FIG. 6.

UNITED STATES PATENT OFFICE.

WALTER N. FANNING, OF VALLEJO, CALIFORNIA.

RADIO SYSTEM.

Application filed March 20, 1922. Serial No. 545,040.

To all whom it may concern:

Be it known that I, WALTER N. FANNING, an officer in the United States Navy, and a resident of Vallejo, in the county of Solano, ⁶⁰ State of California, am the inventor of a new and useful Radio System, of which the following is a specification.

My invention relates to a system of radio communication, and more particularly to a ¹⁰ receiving system controlled from a distant source of radiations.

One of the important adaptations of my invention comprises a system adapted to be placed on board ship and arranged to operate a signal, an alarm, or any other device ¹⁵ only upon the receipt of a certain definite call by radio. Thus the device may be arranged to respond only to the distress call SOS, or several devices may be used, each arranged ²⁰ to respond to a different lighthouse or lightship call. The latter arrangement is particularly useful when, for example, vessels engaged in coastwise trade use substantially identical routes again and again. With such ²⁵ an arrangement, it is possible, by proper adjustment of the receiving apparatus, to pick up a lighthouse or lightship signal when the vessel is at a predetermined distance from the lighthouse or lightship. In this ³⁰ way it is easy to obtain a definite idea of the ship's bearing.

My invention may be used as a distress calling system either alone or in combination with other calling systems such as the ³⁵ usual ship's call, or the lighthouse calls mentioned hereinbefore. Under any circumstance, however, the automatic operation of the local alarm circuit obviates the necessity of having a radio operator on duty at all ⁴⁰ times. For this purpose the alarm bell or other signal would be placed near the operator's bunk. The circuit, however, can be conveniently used to control any number of ⁴⁵ alarms, so that they may be distributed on board ship at the places where the persons interested may become aware of the receipt of the signal.

It is thus one of the objects of my invention to make it possible to call a station selectively by radio; that is, a definite order ⁵⁰ of dots and dashes, and only that order, will operate a local signal circuit.

Another possible application of my invention is to the control of distant objects, ⁵⁵ such as torpedoes or airplanes, by radio. Any number of selective circuits may be

used, each for controlling the body in a certain manner, and the control is effected only upon the receipt of a definite order of dots and dashes. ⁶⁰

My invention possesses other advantageous features, some of which, with the foregoing, will be set forth at length in the following specification where I shall outline in full that form of the invention which I ⁶⁵ have selected for illustration in the drawings accompanying and forming part of the present specification. In the drawings I have shown but one embodiment of my invention, but it is to be understood that I do ⁷⁰ not limit myself to that form, since the invention as expressed in the claims may be embodied in other forms as well.

Referring to the drawings:

Figure 1 shows a wiring diagram of a receiving system utilizing a plurality of selector relays; ⁷⁵

Figs. 2, 3, 4, 7 and 8 show details of construction of the selector relay used in my invention; ⁸⁰

Fig. 5 is a side view, partly in section, of the selector relay; and

Fig. 6 is a view from the other side of the selector relay.

It is essential, in order that a system of the sort mentioned heretofore operate, to provide a primary relay operating the selector, which primary relay will faithfully follow the telegraphic signal. Such a primary relay must not only operate at telegraphic speed, but it must also have sufficient mechanical power to operate the contacts controlling the selector circuit. In Fig. 1, the electromagnetic relay 11 is especially adapted for use in my present invention since it fulfills satisfactorily the requirements enumerated hereinbefore. The relay ⁹⁰ 11 and its associated receiving circuit is but one embodiment of several forms of relaying devices, described and claimed in my co-pending application, Serial Number 531,121, filed January 23, 1922, and entitled "Radio receiving system." ⁹⁵

In the form illustrated in Fig. 1, the telegraphic relay 11 is operated both by the compensating wave and the telegraphic wave. In other words, the signal produced by relay 11 has its power increased by the compensating wave. The antenna circuit ¹⁰⁵ 12 which receives the radio signals is shown in this instance as inductively coupled to two systems labeled respectively T and C. These ¹¹⁰

systems are substantially similar, the system T being adapted to receive the telegraphic signals, and the system C being adapted to receive the compensating wave between signals. Since these two systems are similar, it will be sufficient to describe but one of them. The system T comprises a pair of 3-electrode tubes or audions 13—14 arranged to rectify both half-waves of the received signal. For this purpose, there is interposed between the tubes 13 and 14 and the antenna circuit 12, a transformer 15, the primary of which consists of two coils in parallel. The secondary coils 16 and 17 are joined together 10 at the point 18 and their free extremities are connected to the grid elements 19 and 20 of the tubes 13 and 14. The filaments 21 and 22 are adapted to be heated in any well known manner, not shown, and are connected together at the point 23. A battery 24 is connected between the points 18 and 23. It is thus seen that the input circuit of each tube 13 or 14 comprises the battery 24, one of the coils 16 or 17, a filament, and a grid. 25 The plates 25 and 26 are likewise connected together, and between the points 27 and 23 is connected the output circuit of the system T. This output circuit includes the battery 28 and the wires 29 and 30. It is believed 30 that the operation of this system to rectify the signal is apparent. By properly tuning the receiver circuit system, as by manipulation of an inductively coupled coil 31 and the variable condenser 32, this system may 35 be made sensitive to the telegraphic signals.

The system C has elements substantially similar to the system T, its receiving elements consisting of the coil 33 and condenser 34 tuned to be sensitive to the compensating 40 wave between signals. The wires 35 and 36 leading from system C correspond with the wires 29 and 30 of the system T.

The relay 11 is so connected to both of the 45 systems T and C that while no signal is received, a pivoted armature 37 is held against the right hand pole piece 38 of the relay core. Upon the receipt of an impulse, this armature 37 is not only repelled from the pole 38, but it is attracted to the left hand pole 39. When the impulse ceases, there is 50 a repulsion between the left hand pole piece 39 and the armature 37, and it returns to its former position against the pole piece 38. To obtain this result the armature 37 is 55 polarized; that is, it consists of either a permanent magnet or an electromagnet having its free end either a north or south pole. In the present instance, it is shown as a south pole. The output circuit of the compensating wave system C is connected in series with 60 two coils 40 and 41 which are conveniently disposed on the opposite legs of the relay core, the direction of magnetization produced by these coils being, for example, 65 that shown by the arrows 42 and 43. It is

evident that while no signaling impulses are being received the coils 40 and 41 are energized from the system C and produce a north pole at 38 and a south pole at 39. The result, of course, is that the south pole of 70 the pivoted armature 37 is attracted to the north pole 38. As soon as a signaling impulse is received, however, the coils 40 and 41 become inactive and instead the coils 44 and 45 receive appreciable energy from the 75 system T. These coils are arranged to produce a magnetization in a direction opposite to that produced by the coils 40 and 41. The result is that poles 38 and 39 change their polarity, and the armature 37 80 swings to the left while the impulse is being received and contact is made between wires 46 and 47. The systems T and C are so proportioned that the magnetizing effects of the coils 40 and 41 are substantially equal to 85 the magnetizing effects of the coils 44 and 45. The energy received from the compensating waves in system C is useful in moving the armature 37 back to its position when no signaling impulse is received. In 90 this way a strong movement of armature 37 is obtained. Other advantages of this scheme are detailed at length in my prior application hereinbefore identified. It is 95 of course evident also that it would be possible to rectify only one-half of the wave in each case, instead of both halves, as described.

The system just described may be used 100 equally as well when uni-wave signals are received; that is, when there is no compensating wave filling in the gaps between the signaling waves. Under such circumstances, the system C is tuned to be 105 sensitive to a frequency just sufficiently different from the frequency of the signal waves so that it cannot receive any appreciable signaling energy. The amount of energy received by the system C would then depend upon the interfering waves, and 110 since these interfering waves would have substantially the same effect on the systems T and C, they would be cancelled out by the differential connections of coils 40, 41 and 44, 45. The armature 37 would not be affected in any way by these disturbances. 115

It may sometimes be advisable to insert a condenser 48 in one of the grid circuits, and a resistance 49 bridging it, of comparatively large ohmic value.

The provision of a powerful and speedy relay of the kind just described is an essential to the proper operation of a selector system, and in the past a successful selector system could not be developed partly on this 125 account. The selector relay 50 itself may take any of several forms. There may, of course, be a plurality of selectors operated from the same receiving system, each adapted to close a circuit only after a predeter- 130

mined number of dot and dash signals occur in a definite sequence. I show two selectors 50 and 51, which are substantially similar except for those elements which determine the signals to which they are responsive. The circuit formed by the wires 46 and 47 include the source 52 of electrical energy, and the coils 53 and 53' of the selectors. Since both selectors operate on the same principle, but one of them will be described, and that only sufficiently to expose its operation.

The core 54 has an armature 55 which is held in the open position, when no signaling impulses are received by a flat bowed spring 56 fixed at one end and connected at the other to the free end of the armature 55. Upon the energization of the coil 53, due to the closure of the contacts by armature 37 of relay 11, the spring 56 is pulled flat by the armature 55. This rotates a pivoted arm 57 by means of the connection 58 between it and the bowed spring. This arm carries a driving pawl 59 at its free end, adapted to engage the teeth of a ratchet wheel 60. A retaining pawl 61 is adapted, under certain conditions only as explained hereafter, to hold the wheel 60 in the position it had been moved to by the driving pawl 59. A counterweight 65 may conveniently be used to urge the wheel 60 constantly in a clockwise direction. The ratchet wheel 60 has secured to it an arm 62 carrying a contact 63 which is adapted to cooperate with a stationary contact 64. The contacts engage and complete a circuit after a definite number of movements of the pawl 59, provided the proper sequence of dots and dashes cause this number of movements. Just how this is effected will now be explained with the aid of Figs. 3, 4, 5 and 6.

The retaining pawl 61 has its plane slightly displaced and at a slight angle from that of the wheel 60, as shown in Fig. 8, which is a view taken from the left of Fig. 5; but there extends from the pawl a lip 66 toward the wheel, which lip is arranged to cooperate with the wheel. A stop pin 67 is carried by the wheel 60 and engages the pawl as shown, which lifts the pawl into engagement with the teeth for the start of the signal, when the wheel is in the starting position. A retaining hook 68 engages a lip 69 on pawl 61 and holds this pawl in such a position that it is in position to engage the top half of the ratchet teeth, as shown. If the teeth of ratchet wheel 60 were of the usual kind, it is evident that every impulse of the driving pawl 59 would serve to advance the wheel by a tooth, and after a number of impulses, the contacts 63 and 64 would be made. However, an arrangement is provided to cause disengagement of the hook 68 from the pawl 61 if the impulse received is long enough to be a dash. Under such cir-

cumstances, the lip 66 drops to the bottom half of the tooth.

Now by properly shaping the teeth, it is possible to arrange matters so that the pawl 61 holds the wheel only when it is at the top of certain teeth, and at the bottom of certain others. The manner of shaping the teeth is clearly disclosed in Figs. 2, 3, and 4. Thus the bottom half of tooth 70 is cut away at an angle, as shown by the dotted line 71, and if the pawl 61 happens to be at the bottom of the tooth after the driving pawl 59 is pulled away from the teeth, this inclined surface of the tooth would permit the lip 66 to ride over it, and the pawl 61 would be pressed laterally away from the wheel 60. When this occurs, the pawl 61 rotates downward and away from the wheel 60, due to the fact that its supporting shaft 89 is inclined in the manner shown in the front view, Fig. 8. The pawl moves far enough away to free the lip 66 entirely from the teeth, but it is limited by appropriately formed stops, such as 88, shown in the plan view of Fig. 7. As soon as the lip 66 leaves the teeth, the counterweight 65 is free to act. The wheel returns to its starting position, and the lip is automatically returned to the proper starting tooth by aid of the inclined pin 67 carried by the wheel 60. This pin cooperates with the under surface of the pawl to lift it up and toward the wheel 60.

If however the pawl is at the top of tooth 70, it can hold the wheel. Tooth 72 is on the contrary cut away at an angle 100 at the top, so that when this tooth passes under the pawl 61, the pawl must be at the bottom of the tooth to hold the wheel. The teeth of the wheel 60 may be arranged at will in such a way that a definite sequence of dots (corresponding to teeth cut away at the bottom) and dashes (corresponding to teeth cut away at the top) serve to advance the wheel properly. If the sequence is incorrect, the counterweight 65 returns the wheel 60 to its starting position immediately the driving pawl 59 is disengaged from the teeth of wheel, after the first wrong sequence.

The mechanism for releasing the hook 68 upon the receipt of a long impulse corresponding to a dash is most clearly illustrated in Fig. 6. A pivoted lever 73 is pivotally connected at its free end with a link 74 made up of a pair of separated strips. At the end of link 74 there is pivoted a time wheel 75 arranged to roll on a slightly inclined track 76. When the wheel 75 is permitted to roll down the track, the central portion of link 74 engages a projection 77 on a lever 78, and rotates it. This lever is rigidly connected to a pivoted rod 79, to which is also rigidly connected the hook 68, and when the time wheel rolls down the track 76 far enough, 125

it is evident that the hook 68 permits the pawl 61 to drop to the bottom of the teeth. The inclination of track 76 and the proportioning of the time wheel 75 are such that it requires an impulse equivalent to a dash to rotate the lever 78 far enough to disengage the hook 68. A stop 80 is carried by a stationary part of the mechanism to engage the link 74 upon the return of the time wheel on the track. The time wheel 75 is held up the track and is permitted to roll down only when an impulse is received. The lever 81 is used to hold the wheel in position at all other times. This lever, as shown in Fig. 5, is connected to the pivoted lever 57, and when the armature 55 is attracted, it frees the time wheel and allows it to perform its timing function. Upon release of the armature the lever 81 moves back to the position shown in the figures, and returns the time wheel to the upper part of track 76. At the same time, the movement of the wheel up the track moves the hook 68 so that it may move by gravity into engagement with the lip 66 in case the next impulse is a dot.

The series of teeth on the ratchet wheel 60 may be arranged so that the selector will operate to close a local circuit only when an SOS call is received, or when the ship's call is received. In order to insure proper operation of the timing function in case the device is used on ship board, it is advisable to support the selector in gimbals, so that it may remain truly horizontal.

The local circuit completed by the selector 50 may include one or more alarm bells 82 or other signaling devices, and a source of electrical energy 83. The arrangement may be such that the contacts 63 and 64 need engage for but a short time, and still permit the alarms to sound until manually disconnected. In this way, the receipt of subsequent signals cannot stop the alarm. For this purpose an electromagnet 84 may be connected in parallel with the signaling devices 82, having a pair of front contacts 85 and 86. These contacts are arranged to bridge the selector contacts. Thus when the selector contacts operate, they are immediately bridged by contacts 85 and 86, and the devices 82 are active until the electromagnet 84 is de-energized manually, as by a switch 87.

There may be any number of selectors such as 50 and 51 operated from the same receiver circuit. One of them may be arranged to the distress call, another to the ship's call, and others to the signals radiated from fixed points such as lighthouses. The success of such a system is partly due to provision of a reliable relay such as 11 which can be operated by received energy at telegraphic speed. The complete system lends itself to many uses. A great saving

in expense may be had by dispensing, by this means, with the services of more than one radio operator on ship board. A single radio operator can be easily reached upon receipt of a signal requiring his attention. 70

The local circuit may of course be utilized for a controlling function in place of a signaling function. The system is especially applicable to the distant control of airplanes or torpedoes equipped with such a receiving system. One selector may control for example the operation of the vertical rudders, another the operation of the horizontal rudders, still another the source of motion, and still another the ignition of a charge or the release of a bomb. 80

I claim:

1. In a radio receiving system, an absorbing circuit, a thermionic device responsive to telegraphic signals received in the absorbing circuit, a thermionic device responsive to energy received between signals, an electromagnetic relay having a polarized armature, said relay being arranged to move the armature in one direction on receipt of a signal, 85 by aid of the first mentioned thermionic device, and in another direction on cessation of the signal, by aid of the second mentioned thermionic device, and a selector controlled by said armature, said selector comprising 95 a pair of relatively movable contacts that are operated only upon the receipt of a predetermined, freely selected order of telegraphic dot and dash signals.

2. In a radio receiving system, an absorbing circuit, an electromagnetic telegraphic relay having a polarized armature, means for moving the armature in one direction in response to received telegraphic signals, means for moving the armature between signaling impulses in the opposite direction, and a selector controlled by said armature, 105 said selector having a pair of relatively movable contacts that are operated only upon movement of the armature in a predetermined sequence corresponding to a definite telegraphic dot and dash signal. 110

3. In a radio receiving system, an absorbing circuit, an electromagnetic telegraphic relay having an armature, a selector controlled by said armature, said selector having a pair of relatively movable contacts that are operated only upon movement of the armature in a predetermined sequence 115 corresponding to a definite telegraphic dot and dash signal, and means for causing the electromagnet to respond to telegraphic signals received in the absorbing circuit, comprising a thermionic device responsive to the received energy, said device having 120 a heated filament, a control electrode, and a plate electrode, a source of electrical energy connected to the electromagnet and in circuit with the plate electrode, and means for producing a substantial flow of electri- 125

cal energy in this plate circuit only upon receipt of a signaling impulse.

4. In a radio receiving system, an absorbing circuit, an electromagnetic telegraphic relay having an armature, means responsive to energy received in the absorbing circuit for operating the armature substantially in step with the receipt of telegraphic dot and dash signals, and a selector controlled by the

be engaged by the pawl to advance it, a contact moved by the wheel, a holding pawl, and means for controlling the position of the holding pawl whereby on receipt of a long impulse, it may cooperate only with certain of the teeth to hold the wheel, and upon receipt of a short impulse, it may cooperate only with certain other teeth to hold the wheel.

In testimony whereof, I have hereunto set my hand.

WALTER N. FANNING.
